(57) **CLAIM**

The ornamental design for an electric hair comb handle as shown and described.

DESCRIPTION

FIG. 1 is a front, right and top perspective view of an electric hair comb handle, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof.

FIG. 8 is an enlarged bottom plan view thereof.

FIG. 9 is another front, right and top perspective view in an alternate position thereof.

FIG. 10 is another front, right and top perspective view shown in use with an attachment thereof.

FIG. 11 is another front, right and top perspective view shown in use with another attachment thereof; and,

FIG. 12 is an enlarged view of detail 12 in FIG. 1.

The dashed broken lines depict portions of the electric hair comb handle that form no part of the claimed design.

The dot-dash broken lines in FIGS. 1 and 12 depict the boundaries of the enlargements and form no part of the claimed design.
